(57) **CLAIM**

I claim the ornamental design for cup holder supported positionable tablet holder, as shown and described.

DESCRIPTION

FIG. 1 is an isometric top, side and back view of the cup holder supported positionable tablet holder showing my design.

FIG. 2 is an orthographic front view thereof.

FIG. 3 is an orthographic back view thereof.

FIG. 4 is an orthographic left side view thereof.

FIG. 5 is an orthographic right side view thereof.

FIG. 6 is an orthographic top, downward looking view thereof; and,

FIG. 7 is an orthographic bottom, upward looking view thereof.
